BRIQUETTING PRESS

Leslie S. Hubbert, Mount Gillead, Ohio, assignor
to The Hydraulic Development Corporation,
Inc., Wilmington, Del., a corporation of Dela-
ware

Application April 2, 1943, Serial No. 481,585

7 Claims. (Cl. 18—16)

This invention relates to presses and, in particular, to briquetting presses for powdered and granular materials.

It is an object of this invention to provide a briquetting press, in which the mold for receiving the material to be briquetted is composed of a plurality of mold parts, movable relative to each other during the pressing operation and adapted, following the completion of the pressing operation, to cooperate with each other so as to strip the briquetted article from at least one of said mold parts.

It is another object of this invention to provide a briquetting press having a reciprocable mold portion which is positively actuated by the press ram in response to a predetermined position thereof during the working stroke of said ram, and which is operable independently of said ram, following the completion of the working stroke of said ram.

It is a further object to provide a briquetting press for forming hollow articles which includes a reciprocable outer mold portion and a reciprocable inner mold portion, and in which said outer and inner mold portions are actuated automatically, following the completion of the briquetting operation, to strip the work piece therefrom.

It is still another object of the invention to provide a briquetting press including a reciprocable mold, composed of a plurality of parts movable relative to each other during the actual briquetting operation, while means is provided opening said mold, following said briquetting operation, to allow removal of articles, having an irregular shape, from the said mold.

These and other objects and advantages of the invention will appear more clearly from the following specification in connection with the accompanying drawings, in which:

Figure 1 diagrammatically illustrates a briquetting press according to the invention.

Figure 2 illustrates, partly in section, an article formed by the press of Figure 1.

Figure 3 is a wiring diagram for an electric control circuit to be used in connection with the press according to Figure 1.

Figures 4, 5, 6 and 7 diagrammatically illustrate various phases of operation of the press shown in Figure 1.

Figure 8 is a somewhat modified briquetting press according to the invention which is particularly adapted for briquetting irregularly shaped articles.

Figure 9 is a view of an article formed in the press constructed according to Figure 8.

Figure 10 is a section along the line 10—10 of Figure 8.

Figure 11 is a partial section along the line 11—11 of Figure 10.

Figure 12 is a wiring diagram for use in connection with the structure of Figure 8.

FIRST EMBODIMENT

Structural arrangement

10 Referring now to the drawings and Figure 1 hereof in particular, the system shown therein comprises a press cylinder 20 having reciprocably mounted therein a press ram 21. Connected to the press ram 21 is a press platen 22 which carries a mold portion 23 with a bore 24 therein. The mold portion 23 is adapted to enter a molding cylinder 25 provided in and forming a part of a beam or plate 26. The plate 26 has adjustably mounted therein abutment screws or bolts 27 adapted to be engaged by the platen 22. The plate 26 has furthermore connected thereto plungers 28 and 29 which are respectively reciprocable in stationarily mounted cylinders 30 and 31.

25 The cylinders 30 and 31 are hydraulically interconnected by means of conduits 32 and 33. The conduit 32 is connected to a conduit 34 having one end in fluid communication with the upper end of the cylinder 31, while the other end of the conduit 34 leads to a 4-way valve, generally designated 35. The 4-way valve 35 may be of any standard design and comprises a valve member 36 which is continuously urged into its lowermost position by means of a spring 37.

30 In this position, the valve member 36 establishes fluid connection between the conduit 34 and the conduit 38, while simultaneously interconnecting the conduits 39 and 40. The conduit 39 is connected with the lower portion of the cylinder 31, while the conduit 40 leads to a conduit 41 one end of which is connected to a 4-way valve, generally designated 42.

35 The 4-way valve 42 is of similar structure as the valve 35 and comprises a valve member 43 continuously urged into its lowermost position by means of a spring 44.

In this position, the valve member 43 establishes fluid connection between the conduit 41 and the conduit 45 leading to the lower portion of the cylinder 20, while simultaneously establishing fluid connection between the conduit 46 and the conduit 47 leading into the upper portion of the cylinder 20. Connected to the conduit 47 by means of a pilot line 48 is a tonnage control valve, generally designated 49.

40 The valves 35 and 42 are provided with

solenoids S1 and MS, respectively, adapted to counteract the springs 37 and 44 to move the valves 36 and 42 into their uppermost position. In this position, the valve member 36 connects the conduits 34 and 40 with each other, while simultaneously connecting the conduit 38 with the conduit 39. Similarly, when the solenoid MS is energized, the valve member 43 establishes fluid connection between the conduits 41 and 47, while hydraulically interconnecting the conduits 46 and 45.

The conduit 41 is connected through a conduit 58 with the pressure side of a variable delivery pump 51 which may be of any standard design and is provided with control means 52 connected through a pilot line 53 with the conduit 58 for moving the pump 51 into substantially neutral or no delivery position in response to a predetermined pressure in the conduit 58. The suction side of the pump 51 is connected through a conduit 54 with a fluid reservoir or tank 55. The conduit 54 is connected through a conduit 56 with the conduit 46 which latter leads to a 4-way valve, generally designated 57. The valve 57 corresponds in its structure to the valves 35 and 42.

The valve member 58 is continuously urged into its lowermost position by a spring 59, in which position fluid connection is established between the conduits 41 and 60, while simultaneously the conduits 46 and 61 are connected with each other. The valve 57 has also associated therewith a solenoid S2 adapted to counteract the spring 59 so as to move the valve member 58 into its uppermost position. In this position, the conduit 61 is connected with the conduit 41, while the conduits 60 and 46 are connected with each other.

The conduits 60 and 61 lead to the upper and lower portions, respectively, of a control cylinder 62. Reciprocably mounted in the control cylinder 62 is a plunger 63 connected to a beam or plate 64 which latter has connected thereto adjustable abutment screws 65 for abutment with a stationary beam or plate 66. The plate or beam 66 is also provided with adjustable abutment screws 67 for abutment with the plate or beam 66.

The plate or beam 66 is provided with a sleeve 68 and furthermore carries a mold element 69 having the shape of a hollow cylinder and adapted to fit into the molding cylinder 28. The upper surface of the mold element 69 forms the greatest part of the bottom of the mold composed of the elements 23, 25 and 69 and also of the core plunger 70 which latter is supported by the beam or plate 64 and extends through the sleeve 68 and the mold element 69.

The system shown in Figure 1 also comprises a limit switch LS1 which is normally in open position and is closed by upward movement of the beam or plate 66. A similar limit switch LS3 is provided which is normally in closed position and adapted to be opened by downward movement of the beam or plate 66. The beam or plate 64 is also adapted in response to a predetermined position thereof to engage and close a normally open limit switch LS2, while in another position of the beam or plate 66 the latter opens a normally closed limit switch LS4. The remaining part of the system shown in Figure 1 and enclosed by a dot-dash line is not necessary for the device of Figure 1 if articles, such as the article shown in Figure 2, are formed, whereas it is useful in connection with the forming of irregularly shaped articles, such as the article shown in Figure 9, as will be described later.

Referring to Figure 3 illustrating the wiring

diagram for the electric control circuit pertaining to Figure 1, this diagram comprises the main supply line 71 adapted by closure of the normally open starter switch ST to be connected with the line 72 which latter is adapted by closure of the limit switch LS1 to be connected with a line 73. The line 73 is adapted by closure of the limit switch LS2 to be connected with the line 74. When the tonnage control valve 48 is closed, its switch blade T1 connects the line 74 with one end of a contactor A, the other end of which is connected with the main supply line 75.

The tonnage control blade T1 is connected with a second tonnage control blade T2 in such a manner that when the blade T1 is closed the blade T2 is open and vice versa. The contactor A controls the normally open switches A1 and A2 in such a manner that energization of the contactor A causes the switches A1 and A2 to close, while de-energization of the contactor A causes the said switches to open.

When the switch A1 is closed, it electrically connects the main supply line 71 through the line 76 with the line 73. When the switch A2 is closed it connects the main supply line 71 with one end of the solenoid MS, the other end of which is connected to the main supply line 75. Closure of the blade T2 establishes electric connection between the main supply line 71 and the line 77, which latter is electrically connected by closure of the limit switches LS3 or LS4 with one end of the contactor B, the other end of which is connected to the main supply line 75.

The contactor B controls the normally open switches B1, B2 and B3 in such a manner that these switches are closed when the contactor B is energized, while de-energization of the contactor B causes the switches B1, B2 and B3 to open. Closure of the switch B1 electrically bypasses the blade T2. Closure of the switch B2 closes the energizing circuit for the solenoid S1, while closure of the switch B3 establishes an energizing circuit for the solenoid S2.

45

Operation

It may be assumed that the elements of Figure 1 so far described occupy the position shown therein, while the mold cylinder 28 has been filled with molding material, for instance with powdered material. In order to start a briquetting operation, the operator starts the pump 51 and closes the starter switch ST. Closure of the starter switch ST establishes an energizing circuit for the contactor A which circuit comprises the main supply line 71, switches ST, LS1, LS2, contactor blade T1, contactor A and main supply line 75.

As a result of the energization of the contactor A, the contactor switches A1 and A2 close. Closure of the contactor switch A1 establishes a holding circuit for the contactor A so that the latter remains energized when the operator withdraws his hand from the starter switch ST so that the latter again opens automatically. Closure of the contactor switch A2 establishes an energizing circuit for the main solenoid MS so that the latter moves the valve member 43 into its uppermost position.

Consequently, pressure fluid delivered by the pump 51 now passes through conduits 58, 41 and 47 into the upper portion of the cylinder 28 where it acts upon the ram 21 and moves the latter downwardly. The fluid expelled from the lower portion of the cylinder 28 during this downward

75

movement escapes through conduits 45, 46 and 58 into the conduit 54 and tank 55.

When the ram 21 has moved downwardly to such an extent that the mold portion 23 enters the molding cylinder 25, it begins slightly to compress the material in the molding cylinder, while the core plunger 70 begins to enter the bore 24 in the mold portion 23. It may now be assumed that the mold portion 23 has moved from Figure 4 position into Figure 5 position so that the platen 22 engages the abutment screws 27.

It will now be clear that further downward movement of the ram 21 actuates the plate or beam 26 through the platen 22 and the abutment screws 27 so as to carry the beam or plate 26 along. Consequently, due to the friction between the material in the mold cylinder 25 and the latter, pressure is now exerted upon the upper and lower portion approximately evenly upon the material in the mold cylinder. In this way, a uniform molding pressure is exerted upon the material in the mold cylinder.

Due to the downward movement of the beam or plate 26, also the plungers 28 and 29 move downwardly and pressure fluid in the lower portion of the cylinders 30 and 31, respectively, is conveyed through conduits 33, 39 and 40 into the conduit 41 from where it is conveyed into the upper portion of the cylinder 20. As a result of the downward movement of the beam or plate 26, the switch LS1 is disengaged and therefore opens. This, however, has no effect on the circuit since the switch LS1 is by-passed by the now closed contactor switch A1, and the line 16.

When the ram 21 and therefore also the mold portion 23 and the beam or plate 26 have moved from Figure 5 into Figure 6 position, the actual briquetting operation has been completed. At this time a predetermined pressure has built up in the upper portion of the cylinder 20 which pressure is conveyed through conduit 47 and pilot line 48 to the tonnage control valve 49. In response to this pressure, the tonnage control valve 49 causes its blade T1 to open and its blade T2 to close.

Opening of the blade T1 breaks the energizing circuit for the contactor A so that the contactor switches A1 and A2 open. Opening of the contactor switch A1 has no additional effect at this time, while the opening of the contactor switch A2 breaks the energizing circuit for the main solenoid MS. As a result of the de-energization of the solenoid MS, the spring 44 moves the valve member 43 of the 4-way valve 42 downwardly. Therefore, pressure fluid delivered by the pump 52 now passes through conduits 50, 41 and 45 into the lower portion of the cylinder 20 and causes the ram 21 to return to its uppermost position.

Closure of the blade T2 establishes an energizing circuit for the contactor B so that the contactor switches B1, B2 and B3 close. Closure of the contactor switch B1 establishes a holding circuit for the contactor B so that the latter remains energized when the tonnage control valve 49 returns to its original position after the pressure in the conduit 47 has subsided. The closure of the contactor switches B2 and B3 causes energization of the solenoids S1 and S2.

As a result thereof, the valve members 36 and 58 move into their uppermost position. Therefore, pressure fluid delivered by the pump 51 now passes through conduits 41, 48 and 34 into the upper portion of the cylinders 31 and 30 and 75

similarly pressure fluid delivered by the pump 51 is conveyed through conduits 41 and 61 into the upper portion of the cylinder 62.

It will therefore be clear that the pressure in the upper portion of the cylinders 30 and 31 causes the plate or beam 26 to move further downwardly into the position shown in Figure 7, while the core plunger 70 is withdrawn from the molding cylinder 25 as likewise shown in Figure 7. In this way, the molded article is stripped from the molding cylinder and the core plunger 70 and now rests on top of the beam or plate 26.

It may be assumed that while the beam or plate 26 has reached its lowermost position, the core plunger 70 is still moving downwardly. When the plate 26 has reached its lowermost position it opens the switch LS3. This, however, has no effect yet on the energization of the contactor B since the plunger 70 has not reached its lowermost position at which it opens the limit switch LS4.

However, when the plunger 70 has moved downwardly so as to cause the beam or plate 64 to open the limit switch LS4, the energizing circuit for the contactor B is broken. The contactor B is therefore de-energized and the contactor switches B1, B2 and B3 open. While the opening of the contactor switch B1 has no additional effect at this time, the opening of the contactor switches B2 and B3 causes de-energization of the solenoids S1 and S2. Consequently, the springs 37 and 59 pertaining to the valves 35 and 51, respectively, return these valves to their original downward position so that pressure fluid delivered by the pump 51 causes the plungers 28 and 29 to return the plate or beam 26 to its uppermost position, while fluid delivered by the pump 51 into the lower portion of the control cylinder 62 causes the plunger 63 to lift the core plunger 70 into its uppermost position. The press elements then again occupy the position shown in Figures 1 and 4 while, however, the briquetted article 78 rests on top of the mold element 69.

The operator then removes the article 78 and the mold cylinder 25 may be charged with a new charge of material to be briquetted. Since the plungers 28, 29 and 70 and the ram 21 now occupy their uppermost position, the pressure in the conduit 50 will increase, to such an extent that, conveyed through pilot line 53, it will cause the control means 52 to move the pump 51 to substantially neutral or no delivery position. The pump will remain in this position until a new cycle is started in the manner described above.

From the above description, it will be clear that the system of Figures 1 and 2 comprises a safety feature which prevents the starting of a new cycle before the various parts have reached their initial position. More specifically, the closure of the starter switch ST will not be able to cause energization of the contactor A and thereby of the main solenoid MS unless the plate or beam 26 has been fully retracted so as to close the limit switch LS1, and unless the core plunger 70 has been fully lifted so that the plate or beam 64 closes the limit switch LS2.

SECOND EMBODIMENT

Structural Arrangement

Referring now to the embodiment shown in Figures 8 and 10 to 12, the press shown therein differs from that of Figure 1 primarily in control mechanism for opening the mold cylinder in order to enable the removal of articles with irreg-

ular shape, such as the article shown in Figure 9.

More specifically, the press shown in Figure 8 comprises a press cylinder 88 having reciprocably mounted therein a press plunger 81 which has connected thereto a press platen 82. The press cylinder 88 is connected to the press head 83, which, in its turn, is connected to the press bed 84 by means of strain rods 85 and nuts 86. Mounted on the press head 83 is a fluid reservoir or tank 87 into which the press cylinder 88 extends. The fluid reservoir or tank 87 corresponds to the tank 55 of Figure 1, and the hydraulic connections between the cylinder 88, the tank 87 and the fluid source for delivering pressure fluid to the cylinder 88 are the same as in Figure 1. Therefore, the conduits leading to the cylinder 88 carry the same numerals as in Figure 1.

The press bed 84 carries a plate or beam 88 which corresponds to the beam or plate 66 in Figure 1 and which similarly is provided with adjustable abutment screws 89. The beam or plate 88 has connected to the upper portion thereof a mold element 90 forming the bottom portion of a mold, generally designated 91 (Fig. 11). The mold 91 is composed of a mold portion 92 which is rigidly connected in any convenient manner with the movable plate or beam 88, and furthermore comprises a mold portion 94 which is movable relative to the beam 88.

The mold portion 94 is slidably mounted on the plate or beam 88 and is connected in any convenient manner with a fluid operable plunger 95 reciprocably mounted in a cylinder 96. The arrangement is such that, during the molding or pressing operation, the mold portions 92 and 94 engage each other so as to act as a unitary form. However, when the briquetting operation has been completed, the mold portion 94 is spaced from the mold portion 92 in order to allow the removal of an irregularly shaped article, such as the article 97 shown in the drawings.

The structure of Figure 8 is, in a manner, similar to that of Figure 1 provided with a control cylinder 98 having reciprocably mounted therein a control plunger 99 which, in its turn, has connected thereto a beam or plate 100 corresponding to the beam or plate 64 of Figure 1. The hydraulic connections of the cylinder 98 correspond to those of the cylinder 62 and therefore are designated with the same numerals. Connected to the beam or plate 100 is a core plunger 101 corresponding to the core plunger 70 of Figure 1. A further mold portion 102 is connected to the press platen 82 which mold portion is adapted to enter the mold 91 and takes the place of the mold portion 23 in Figure 1.

Similar to the structure of Figure 1, the press of Figure 8 is provided with adjustable abutment screws 103. In order to prevent the hands of the operator from accidentally getting between the abutment screws 103 and the beam or plate 93, safety guards 104 at least partially surrounding the upper portions of the abutment screws 103 are connected to the platen 82.

To limit the uppermost position of the beam or plate 93, adjustable abutment screws 113 are connected to the cylinders 114 which are connected to the press head 83. Reciprocably mounted in the cylinders 114 are plungers 115 connected to and adapted to reciprocate the beam or plate 93. To prevent the operator's hands from getting caught between the abutment screws 113 and the beam or plate 93, safety guards 116, similar to the safety guards 104, are provided and connected to the beam or

plate 93. Otherwise, the hydraulic circuit for the structure of Figure 8 corresponds to that of Figure 1, the only difference consisting in the supplementary circuit enclosed by a dot-dash line in Figure 1.

This supplementary circuit comprises conduits 105 and 106, respectively, connected to the left end and right end of the cylinder 96 and leading to a 4-way valve, generally designated 107. The valve 107 corresponds in its structure to the valves 35, 42 and 57 and is provided with a valve member 108 continuously urged into its lowermost position by a spring 109. When the valve member 108 is in its lowermost position, the conduit 106 communicates with a conduit 111 leading to the conduit 58, while simultaneously the conduit 105 is connected with a conduit 110 leading into the conduit 41. The valve member 108 is adapted to be moved into its uppermost position by energization of a solenoid AS. In this uppermost position, the valve member 108 establishes fluid connection between the conduits 105 and 111, while simultaneously interconnecting the conduits 106 and 110.

Referring now to Figure 12, illustrating the electric control circuit for the structure of Figure 8, this circuit comprises in part the same elements as the circuit of Figure 2 which are therefore designated with the same numerals as used in Figure 2. In addition thereto, the circuit of Figure 12 comprises a normally open limit switch LS5 which is closed by a dog 112 (see Figure 1) when the plunger 95 has properly moved the mold portion 94 into mold closing position.

When the limit switch LS5 is closed, it electrically interconnects the contactor B and the tonnage control blade T1 when the latter is in its closing position. The tonnage control blade T1 is furthermore connected with an additional tonnage control blade T3 in such a manner that the blade T3 moves into its closing position when the blade T1 moves into its closing position and opens together with the blade T1. The remaining parts of the circuit shown in Figure 12 will best be understood from a description of the operation of the structure illustrated in Figure 8.

Operation

It may be assumed that all parts of the press shown in Figure 8 occupy the position shown therein, while the pump 52 has been started. The operator now closes the switch 0 thereby energizing the contactor A. Energization of the contactor A causes the contactor switches A1 and A2 to close and the contactor switch A3 to open. The opening of the contactor switch A3 has no effect on the circuit at this time.

Closure of the contactor switch A1 establishes a holding circuit for the contactor A so that the latter remains energized when the operator releases the switch 0 and allows the latter to return to its open position. Closure of the contactor switch A2 closes the energizing circuit for the contactor AS so that the valve member 108 moves into its uppermost position. Pressure fluid from the pump 52 is then conveyed through conduits 50, 41, 110 and 106 to the right hand portion of the cylinder 96, thereby moving the plunger 95 toward the left and causing the mold portion 94 to engage the mold portion 92 for closing the mold.

Thereupon, the operator fills the mold 91 with molding material, and after this operation has been completed the press is ready to start a working cycle. To this end, the operator closes the

starter switch ST thereby closing the energizing circuit for the contactor B which circuit comprises the main supply line 11, the now closed starter switch ST, the switches LS1, LS2 closed at this time, the blade T1, the switch LS5, contactor B and main supply line 15. Energization of the contactor B causes the contactor switches B1 and B2 to close.

Closure of the contactor switch B1 establishes a holding circuit for the contactor B so that the latter will remain energized when the operator releases the starter switch ST so that the starter switch returns to its open position. Closure of the contactor switch B2 closes the energizing circuit for the main solenoid MS. Therefore, the valve member 43 moves upwardly, and pressure fluid delivered by the pump 51 passes through conduit 47 into the upper portion of the press cylinder 80 where it causes the ram 81 to move downwardly.

The fluid expelled from the lower portion of the cylinder 80 during this downward movement of the ram 81 escapes through conduits 45, 46 and 56 into the conduit 54 and tank 55. Downward movement of the ram 81 causes the press platen 82 and thereby also the mold portion 102 to move downwardly. When the mold portion 102 has just entered the mold 91 and slightly compressed the material in the mold, the abutment screws 103 engage the plate or beam 93. Further downward movement of the ram 81 will now cause the plate or beam 93 by means of the platen 82 and the abutment screws 103 likewise to move downwardly.

Since the cylinder 96 is mounted on the plate 93, the downward movement of the plate 93 carries along the mold 91. In this way, the molding material in the mold 91 is properly compressed from all sides. When the plate 93 begins to move downwardly, it disengages the limit switch LS1 so that the latter opens. This, however, has no effect on the electric circuit since the contactor B remains energized through the closed contactor switch B1. When the plate 93 has been moved downwardly to such an extent that it abuts the abutment screws 89, it comes to a stop.

At about this time or shortly thereafter, the pressure in the upper portion of the press cylinder 80 has increased to such an extent that it actuates the tonnage control valve 49, thereby causing the blades T1 and T3 of the tonnage control valve to open, while simultaneously causing the blade T2 of the tonnage control valve to close.

The opening of the tonnage control blade T3 breaks the energizing circuit for the contactor A thereby causing the contactor switches A1 and A2 to open, while causing the contactor switch A3 to close. Opening of the contactor switch A1 has no effect on the circuit at this time. Opening of the contactor switch A2 causes de-energization of the solenoid AS. De-energization of the solenoid AS causes the spring 109 of the valve 107 to move the valve member 108 downwardly, thereby conveying pressure fluid from the pump 51 through conduit 105 to the left side of the cylinder 96.

As a result thereof, the plunger 95 moves toward the right and spaces the mold portion 94 from the mold portion 92. The opening of the tonnage control blade T1 breaks the energizing circuit for the contactor B so that the contactor switches B1 and B2 open. Opening of the contactor switch B1 has no additional effect on the circuit at this time. Opening of the contactor

switch B2 breaks the energizing circuit for the main solenoid MS so that the spring 44 pertaining to the valve 42 moves the valve member 43 downwardly and causes pressure fluid delivered by the pump 51 to pass through conduit 45 into the lower portion of the cylinder 80, where the fluid acts upon the ram 81 and moves the latter upwardly. In this way, the mold portion 102 is withdrawn from the mold 91. When the ram 81 has reached its uppermost position, it comes to a stop.

Closure of the tonnage control blade T2 brings about energization of the contactor C so that the contactor switches C1, C2 and C3 close. Closure of the contactor switch C1 establishes a holding circuit for the contactor C so that the latter remains energized when the tonnage control valve 49 and thereby the tonnage control blades T1, T2 and T3 return to their initial position after the ram 81 has started its return stroke.

Closure of the contactor switch C2 establishes the energizing circuit for the solenoid S2 so that the valve member 58 is moved upwardly and pressure fluid delivered by the pump 51 passes through conduits 41 and 61 into the upper portion of the control cylinder 98. Here it acts upon the plunger 99 and moves the latter downwardly, thereby withdrawing the core plunger 101 from the mold.

Since the plunger 99 moves downwardly, the extension 117 connected to the beam or plate 100 disengages limit switch LS2 so that the latter opens. This, however, is without effect on the circuit at this time. When the beam 100 has reached its lowermost position it causes the limit switch LS4 to open. However, inasmuch as the limit switch LS4 is by-passed by the closed switch 118, the opening of the limit switch LS4 has no effect on the circuit.

Closure of the contactor switch C3 establishes the energizing circuit for the solenoid S1 so that the valve member 36 moves upwardly and causes pressure fluid to pass from conduit 50 through conduits 40 and 34 upon the upper portions of the plungers 115, thereby positively maintaining the plate or beam 93 in contact with the abutment screws 89. The operator now removes the briquetted work piece from the mold.

To condition the press for a new working cycle, the operator closes the switch 0, thereby closing the energizing circuit for the contactor A as previously mentioned. As a result thereof, the contactor switches A1 and A2 close while the contactor switch A3 opens. Closure of the contactor switch A1 establishes a holding circuit for the contactor A, while closure of the contactor switch A2 causes energization of the solenoid AS. Energization of the solenoid AS causes the valve member 108 to move upwardly so that pressure fluid from the pump 51 passes toward the right side of the cylinder 96 and causes the plunger 95 to move leftwardly to thereby bring the mold portion 94 into its closing position. When the mold portion 94 has reached its closing position, the dog 112 closes the limit switch LS5.

Opening of the contactor switch A3 breaks the energizing circuit for the contactor C so that the contactor switches C1, C2 and C3 open. Opening of the contactor switch C1 has no additional effect on the circuit at this time. Opening of the contactor switches C2 and C3 causes de-energization of the solenoids S1 and S2. De-energization of the solenoid S1 causes the spring

37 of the valve 35 to move the valve member 36 downwardly.

As a result thereof, pressure fluid delivered by the pump 51 passes through conduits 50 and 39 into the lower portion of the cylinders 114 where it acts upon the plungers 115 so as to move the latter together with the beam or plate 93 upwardly. When the beam or plate 93 has been fully retracted, it again closes the limit switch LS1.

De-energization of the solenoid S2 causes the spring 59 of the valve 57 to move the valve member 58 downwardly so that pressure fluid from the pump 51 passes through conduit 60 into the lower portion of the cylinder 98 and moves the plunger 99 upwardly. In this way, the core plunger 101 is again reintroduced into the mold. When the plunger 99 has reached its uppermost position, the extension 117 has again closed the limit switch LS2. All parts of the press now are again in their initial position and a new cycle may be started in the manner described above.

While the press shown in Figure 8 has been described in connection with the briquetting of articles having an irregular shape, such as the article shown in Figure 9, which irregular shape prevents an ejection or stripping of the briquette article in the manner described in connection with Figure 1, it should be noted that the press of Figure 8 may also operate in the manner of the press shown in Figure 1.

To condition the press of Figure 8 for such an operation, it is merely necessary to shift the selector switch 119 from the position shown in Figure 9 so that it contacts the terminal 120. Furthermore, the switch 118 is opened. From a comparison of the thus conditioned circuit of Figure 12 with the circuit of Figure 2, it will be clear that both circuits then fully correspond to each other.

In other words, the circuit of Figure 12 will then be identical to that of Figure 2, and since, on the other hand, the hydraulic circuits of both presses are the same, Figure 8 will then operate in the same manner as Figure 1.

It is, of course, understood that in this instance the mold portions 92 and 94 would be replaced by mold portions making up a mold for a cylindrical body similar to the mold cylinder 25 of Figure 1.

When the cylinder 96 of Figure 8 is used, it will be clear that a return of the plate or beam 93 and consequently a starting of the press cycle will be possible only after the mold has been closed. This safety feature is embodied by the limit switches LS5 and LS1.

It is, of course, understood that the present invention is by no means limited to the particular structure shown in the drawings, but also embraces such modifications as come within the scope of the appended claims.

Having thus fully described and ascertained the nature of my said invention, what I claim as new and desire to secure by Letters Patent is:

1. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement of said platen and first mold part, a third mold part movable transversely to the direction of

movement of said first and second mold parts, a motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts by said platen motor.

2. In a press, said press having at least three mold parts at least two of which are movable independently of each other and all of which are movable in unison, a platen motor, a first mold part and a platen rigid with the movable motor, a first mold part and a platen rigid with the movable member of said motor, a second mold part positioned to be engaged by said platen and to be moved thereby during the latter part of the movement of said platen and first mold part, a third mold part movable transversely to the direction of movement of said first and second mold parts, a transversely disposed motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts by said platen motor, and an additional motor means connected to one of said mold parts for maintaining the same against said stop means.

3. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement of said platen and first mold part, a third mold part movable transversely to the direction of movement of said first and second mold parts, a motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts and platen by said platen motor.

4. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement of said platen and first mold part, a third mold part movable transversely to the direction of movement of said first and second mold parts, a motor

means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts and platen by said platen motor, and an additional motor means connected to one of said mold parts for maintaining the same against said stop means.

5. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement of said platen and first mold part, a third mold part movable transversely to the direction of movement of said first and second mold parts, a motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts by said platen motor, and an additional motor means connected to said second mold part for maintaining the same against said stop means.

6. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement

of said platen and first mold part, a third mold part movable transversely to the direction of movement of said first and second mold parts, a motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts by said platen motor, and a fourth mold part and motor means therefor for advancing said fourth mold part toward and away from said first mold part and in the same direction of movement as the movement of said first mold part.

10 7. In a press, said press having at least three mold parts at least two of which are movable independently of each other and all of which are movable in unison, a platen motor, a first mold part and a platen rigid with the movable member of said motor, a second mold part positioned to be engaged by said platen and to be moved thereby during the latter part of the movement of said platen and first mold part, a third mold part movable transversely to the direction of movement of said first and second mold parts, a motor means for moving said third mold part into and out of clamping engagement with said second mold part, prior to the engagement of said platen with said second mold part, said third mold part being also capable of movement in the same direction as the second mold part and being moved by said platen while said third mold part is in clamped engagement with said second mold part and during the latter part of the platen movement and stop means for limiting the movement of all of said mold parts by said platen motor, and means responsive to a desired maximum pressure in the space encompassed by said mold parts to simultaneously operate said platen motor, and another of said mold means to mold opening position.

LESLIE S. HUBBERT.
